UNITED STATES PATENT OFFICE.

EDWARD L. ARNDT AND JULIUS I. MARQUART, OF BEAVER DAM, WISCONSIN.

BOTTLE-WASHER.

No. 909,736.

Specification of Letters Patent.

Patented Jan. 12, 1909.

Application filed April 24, 1908. Serial No. 429,027.

To all whom it may concern:

Be it known that we, EDWARD L. ARNDT and JULIUS I. MARQUART, citizens of the United States, residing at Beaver Dam, in the county of Dodge and State of Wisconsin, have invented new and useful Improvements in Bottle-Washers, of which the following is a specification.

This invention relates to bottle washers, the object of the invention being to provide a practical bottle washing and scouring machine embodying in addition to the usual rotary brush for operating on the inside of the bottle, one or more rotary brushes which operate on the outside of the bottle and serve to brush off and effectually remove rust and other accumulation on the outside of the bottle neck caused by the metal crown caps now commonly used in closing the mouths of bottles, the brushes being so combined and arranged as to operate simultaneously and perform their work in a single operation.

With the above and other objects in view, the nature of which will more fully appear as the description proceeds, the invention consists in the novel construction combination and arrangement of parts as herein fully described, illustrated and claimed.

36 In the accompanying drawing:—Figure 1 is a side elevation of a bottle washing machine constructed in accordance with the present invention. Fig. 2 is a plan view thereof. Fig. 3 is a vertical cross section 35 through one end of the machine. Fig. 4 is a horizontal section through the slide frame taken in line with the shafts.

The machine embodies essentially a base 1 upon which is preferably mounted a pan or tray 2 for catching the water. Located upon the base is a guide frame embodying parallel guides 3 preferably in the form of cylindrical rods, and guide supports 4 at opposite ends of the guides, connecting the same rigidly and securely to the base 1.

50 Mounted on the guides 3 and adapted to travel lengthwise thereof, is a slide frame 5 which is provided with a central bearing sleeve 6 slidable lengthwise on a center shaft 7 one end of which is journaled in the hub 8, of a water motor 9 by means of which rotary motion is imparted to said shaft the other end of said shaft having a scouring brush 7' attached thereto. The shaft 7 is provided with a flat side 10 and has mounted

thereon a slide gear 11, the opening of which corresponds with the cross sectional shape of the shaft 10 so that while said gear is caused to rotate with the shaft 7, it is also allowed to move freely lengthwise thereof, 60 being carried by the slide frame 5. In order to accomplish this the gear 11 is provided with a grooved hub, or in other words, said gear embodies a flange 12 which is engaged by the hooked extremity of a clip 13 65 which is secured at 14 to the bearing sleeve 6 of the slide frame. Therefore, as the slide frame moves back and forth of the guides 3, the slide gear 11 is carried with it.

To the opposite or forward end of the 70 bearing sleeve 6 there is secured by means of a bracket 15 an apertured head 16 which is provided with a central thimble 17 surrounding the aperture therein and adapted to receive the neck portion of a bottle, the arrangement being such that by pressing the bottle against the head 16 after inserting the neck of the bottle through the thimble 17, the slide frame 5 is moved toward the motor 9, the return of the slide frame or carriage being effected by means of a spring 19 one end 75 of which is connected to the slide frame while the other end is connected to a bracket 20 secured to the base 1.

In addition to the central bearing sleeve 6, 80 the slide frame carries other bearing sleeves 21 and 22 which are connected with the sleeve 6 and in which are journaled rotary shafts 23 and 24 which carry rotary brushes 25 and 26 at their forward ends which 90 brushes are designed to scour and clean the outside of the bottle neck in the manner indicated by dotted lines in Figs. 2 and 4, this operation taking place while the inside brush is cleaning the interior of the bottle as indicated in Fig. 2. At the ends opposite the brushes 25 and 26 the shafts 23 and 24 are provided with gears 27 and 28 which are in constant mesh with the intermediate slide gear 11 as shown in Figs. 2 and 4. In this 100 way all of the shafts 23 and 24 are simultaneously operated, motion being communicated to the side shafts 23 and 24 from the center shaft 7.

At a suitable point in the backward throw 105 of the slide frame 5, the latter comes in contact with trip fingers 29 on a valve operating rod 30 thereby opening the water inlet valve 31 which controls the water supply pipe 32 leading into the casing of the motor 9, the 110

valve being returned to its closed position when the slide frame moves forward again by means of a spring 33.

The apertured head 16 is made oblong as shown in Figs. 3 and 4 so as to act as a protector or guard for the hands and fingers of the operator by extending over and covering the rotary brushes 25 and 26.

From the foregoing description it will be seen that the brushes operate simultaneously and in a single operation and while scouring and cleaning the inside of the bottle the neck is also scoured and cleaned on the outside, thereby effectually removing all rust caused by the crown caps now in common use by means of which the bottles are sealed.

We claim:

1. In a bottle washing machine, the combination of a rotary brush operating on the inside of the bottle, a rotary shaft carrying said brush, rotary brushes operating on the outside of the bottle, rotary shafts for the last-named brushes, a slide frame in which the last-named shafts are journaled, a guide frame therefor, and means for driving all of said shafts while permitting a relative sliding movement thereof.
2. In a bottle washing machine, the combination of a rotary brush operating on the inside of the bottle, a rotary shaft carrying

said brush, a rotary brush operating on the outside of the bottle, a rotary shaft for the latter brush, means for driving said shaft, a stationary guide frame, a slide frame movable along the guide frame, and gears carried by said slide frame and mounted on the shafts, one of said gears having a sliding engagement with its shaft and the other gear being fast on the shaft of the brush carried by the slide frame.

3. In a bottle washing machine, the combination with a rotary brush operating on the inside of the bottle, a rotary shaft carrying said brush, a rotary brush operating on the outside of the bottle, a rotary shaft for the last-named brush, a slide frame in which the last named shaft is journaled, a guide frame therefor, intermeshing gear wheels for imparting rotary motion to both of said shafts, both of said gear wheels being movable with the slide frame, and an apertured bottle neck receiving head connected with the slide frame, substantially as described.

In testimony whereof we affix our signatures in presence of two witnesses.

EDWARD L. ARNDT.
